WALKING ANIMAL TOY

Robert Sleseman, Saginaw, Mich., assignor of
fifty per cent to Walter F. Klonowski, Saginaw,
Mich.

Application July 14, 1938, Serial No. 219,200

9 Claims. (Cl. 46—149)

This invention relates to walking animal toys. An object of this invention is to provide a strong, durable and attractive toy of the character described, which shall be relatively inexpensive to manufacture, easy to operate, and which shall yet be practical, efficient and amusing to a high degree in use.

Other objects of this invention will in part be obvious and in part hereinafter pointed out.

10 The invention accordingly consists in the features of construction, combinations of elements, and arrangement of parts which will be exemplified in the construction hereinafter described, and of which the scope of application will be indicated in the following claims.

In the accompanying drawing, in which is shown one of the various possible illustrative embodiments of this invention,

20 Fig. 1 is a side, elevational view of a walking animal toy, embodying the invention, and illustrating different positions thereof when walking the toy;

25 Fig. 2 is a side, elevational view of the improved toy, showing the same in still another position; and

Fig. 3 is a cross-sectional view taken on line 3—3 of Fig. 2.

Referring now in detail to the drawing, 10 designates a walking toy, embodying the invention, comprising a flat, thick body 11 of wood, rubber composition, or other suitable material. Said body may have the shape of any suitable toy, for example, a duck, rabbit, or any other animal or object.

35 In the drawing, the body 11, is shown in the shape of a duck, for the purpose of illustration. The same has a head 12, a front portion 13 and a rear portion 14.

The body 11 is formed with a through opening 15, forwardly of the center of gravity of said body. Said body is also formed with an arcuate slot 16, below and concentric with the opening 15. The lower edge 17 of the body is preferably curved. At the front of the body is a downward projection 19, extending below the curved bottom edge 17.

40 Rotatably mounted within the opening 15 is a pivot pin 20, projecting beyond the body 11 on opposite sides, as at 21. Fixed to the opposite ends 21 of the pin 20, are a pair of similar, parallel, flat members 22, simulating wings and feet of a duck. The members 22 may be spaced from opposite sides of the body 11 by washers 23, received on the pin 20, and interposed between said members and said body. Each member 22 has a

bottom portion 24, formed with a curved under-edge 25, disposed below the lower edge 17 of the body 11. The curve 25 is such that the distance from the pivot 20 to the back portion of the curve (near 27) is substantially greater than the corresponding distance to the forward portion. Said members 22 are interconnected by a dowel pin 26, extending through the slot 16. The members 22 are so proportioned that when said members freely hang by gravity from the pin, the rear end 10 27 of the portion 24, will be substantially directly below the pivot pin 20 and in contact with the floor 30.

The through opening 15, and hence the pivot pin 20, are so located on the body 11 that when 15 said body hangs freely by gravity on said pin, the rear portion 14 thereof, will swing downwardly until the pin 26 contacts the rear end of the slot 16.

Screwed to the rear edge of the body 11 is an 20 eyelet 31, to which is attached a string 32 for operating the toy.

The operation of the toy will now be described:

When the toy is placed on a flat or slightly upwardly or downwardly inclined surface 30, the 25 body will swing down to the position shown in full lines in Fig. 1 of the drawing, with the forward ends of portions 24 of members 22, and the rear portion of the body 11 in contact with the surface 30. The toy should be placed about eighteen inches in front of the operator. The operator then pulls upwardly on the string 32, to swing the body in a counter-clockwise direction about the pin 20, bringing the projection 19 downwardly into contact with the surface 30. The 30 body is then pulled up further slightly about the projection 19 in a counter-clockwise direction, raising the level of pivot 20 and freeing the members 22 from engagement with the surface 30. This operation causes the members 22 to swing 40 forwardly in a clockwise direction, bringing the rear ends of portions 24 of said members 22 into contact with surface 30, as shown in Fig. 2 of the drawing. The point of tangency 25a between curve 25 and surface 30 is always rearwardly of 45 the vertical projection of the pivot 20.

Upon lowering the string, the body 11 will swing forwardly about pin 20, in a clockwise direction to bring the toy to the position shown in full lines in Fig. 1 of the drawing. During this 50 last movement, the members 22 will roll on surface 30 forwardly about their lower edges 25, to advance pivot pin 20 and the body 11. This rolling will lower the center of gravity which provides the energy for the step. The toy will walk 55

up an incline provided that the relation between the curve 25 and the pivot 20 is such that the center of gravity is lowered during the forward step and lifted when the string is pulled up.

5 The operation described above is then repeated causing the toy to advance step by step forwardly as the string is lifted and lowered by the operator.

If the toy were in the shape of a rabbit or other four legged animal, the front feet of the animal 10 would take the place of the projection 19.

10 It will thus be seen that there is provided a device in which the several objects of this invention are achieved, and which is well adapted to meet the conditions of practical use.

15 As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:

1. A walking animal toy comprising a body 25 formed with a through opening, and an arcuate slot concentric about and disposed below said opening, a pin within said opening and projecting beyond said body on opposite sides, a pair of similar, parallel members on the projecting ends 30 of said pin, rotatable about the axis of said pin, and disposed on opposite sides of said body, and a member extending through said slot and interconnecting said members, said members having curved undersurfaces, a vertical projection 35 of the pin being forward of the point of tangency of said curved undersurfaces with a flat surface on which the toy is placed, and said curved undersurfaces being such that the distance from the pin to the back portion of the 40 curved undersurfaces, is substantially greater than the corresponding distance of the pin to the forward portion of said undersurfaces.

2. A walking animal toy comprising a body 45 formed with a through opening, and an arcuate slot concentric about and disposed below said opening, a pin within said opening and projecting beyond said body on opposite sides, a pair of similar, parallel members on the projecting ends 50 of said pin, rotatable about the axis of said pin, and disposed on opposite sides of said body, a member extending through said slot and interconnecting said members, and washers on said pin interposed between said body and pair of members, said members having curved undersurfaces, a vertical projection of the pin being 55 forward of the point of tangency of said curved undersurfaces with a flat surface on which the toy is placed, and said curved undersurfaces being such that the distance from the pin to the back portion of the 60 curved undersurfaces, is substantially greater than the corresponding distance of the pin to the forward portion of said undersurfaces.

3. A walking animal toy comprising a body 65 formed with a through opening, and an arcuate slot concentric about and disposed below said opening, a pin within said opening and projecting beyond said body on opposite sides, a pair of similar, parallel members on the projecting 70 ends of said pin, rotatable about the axis of said pin, and disposed on opposite sides of said body, a member extending through said slot and interconnecting said members, an eyelet fixed to the rear of said body, and a string attached to 75 said eyelet, said members having curved under-

5 surfaces, a vertical projection of the pin being forward of the point of tangency of said curved undersurfaces with a flat surface on which the toy is placed, and said curved undersurfaces being such that the distance from the pin to the back portion of the curved undersurfaces, is substantially greater than the corresponding distance of the pin to the forward portion of said undersurfaces.

4. A walking animal toy comprising a body 10 formed with a through opening, and an arcuate slot concentric about and disposed below said opening, a pin within said opening and projecting beyond said body on opposite sides, a pair of similar, parallel members on the projecting ends 15 of said pin, rotatable about the axis of said pin, and disposed on opposite sides of said body, a member extending through said slot and interconnecting said members, an eyelet fixed to the rear of said body, a string attached to 20 said eyelet, said body having a curved bottom edge, and being formed with a projection at the front, extending below said curved bottom edge, said members having curved undersurfaces, a vertical projection of the pin being forward of the point of tangency of said curved undersurfaces with a flat surface on which the toy is 25 placed, and said curved undersurfaces being such that the distance from the pin to the back portion of the curved undersurfaces, is substantially greater than the corresponding distance of the 30 pin to the forward portion of said undersurfaces.

5. A walking animal toy comprising a body 35 formed with a through opening, and an arcuate slot concentric about and disposed below said opening, a pin within said opening and projecting beyond said body on opposite sides, a pair of similar, parallel members on the projecting ends 40 of said pin, rotatable about the axis of said pin, and disposed on opposite sides of said body, a member extending through said slot and interconnecting said members, an eyelet fixed to the rear of said body, a string attached to 45 said eyelet, said body having a curved bottom edge, and being formed with a projection at the front, extending below said curved bottom edge, said pair of members having curved underedges disposed below the curved bottom edge of said body, a vertical projection from the pin being disposed forwardly of the point of tangency of said underedges with a flat surface on which the toy is placed, and said pin being closer to the forward ends 50 of said underedges than to the rear ends thereof.

6. A walking animal toy comprising a body 55 formed with a through opening, and an arcuate slot concentric about and disposed below said opening, a pin within said opening and projecting beyond said body on opposite sides, a pair of similar, parallel members on the projecting 60 ends of said pin, rotatable about the axis of said pin, and disposed on opposite sides of said body, a member extending through said slot and interconnecting said members, and washers on said pin interposed between said body and pair of 65 washers, said pivot pin being disposed forwardly of the center of gravity of said body, whereby the rear of said body tends to swing down by gravity about said pivot pin, said members having curved undersurfaces, a vertical projection 70 of the pin being forward of the point of tangency of said curved undersurfaces with a flat surface on which the toy is placed, and said curved undersurfaces being such that the distance from the pin to the back portion of the 75

curved undersurfaces, is substantially greater than the corresponding distance of the pin to the forward portion of said undersurfaces.

7. A walking animal toy comprising a body formed with a through opening, and an arcuate slot concentric about and disposed below said opening, a pin within said opening and projecting beyond said body on opposite sides, a pair of similar, parallel members on the projecting ends of said pin, rotatable about the axis of said pin, and disposed on opposite sides of said body, a member extending through said slot and interconnecting said members, an eyelet fixed to the rear of said body, a string attached to said eyelet, said body having a curved bottom edge, and being formed with a projection at the front, extending below said curved bottom edge, said pair of members having curved underedges disposed below the curved bottom edge of said body, said pivot pin being disposed forwardly of the center of gravity of said body, whereby the rear end of said body tends to swing down by gravity about said pivot pin, a vertical projection from the pin being disposed forwardly of the point of tangency of said underedges with a flat surface on which the toy is placed, and said pin being closer to the forward ends of said underedges than to the rear ends thereof.
8. A walking animal toy comprising a body formed with a through opening, and an arcuate slot concentric about and disposed below said opening, a pin within said opening and projecting beyond said body on opposite sides, a pair of similar, parallel members on the projecting ends of said pin, rotatable about the axis of said pin, and disposed on opposite sides of said body, a member extending through said slot and interconnecting said members, an eyelet fixed to the rear of said body, a string attached to said eyelet, said body having a curved bottom edge, and being formed with a projection at the front, extending below said curved bottom edge, said pair of members having curved underedges disposed below the curved bottom edge of said body, said pivot pin being disposed forwardly of the center of gravity of said body, whereby the rear end of said body tends to swing down by gravity about said pivot pin, a vertical projection from the pin being disposed forwardly of the point of tangency of said underedges with a flat surface on which the toy is placed, and said pin being closer to the forward ends of said underedges than to the rear ends thereof.
9. A walking animal toy comprising a body, a member pivoted to the body and having a curved underedge disposed below the lower edge of the body, a string attached to the rear of the body, a vertical projection from the pivotal connection of said member being disposed forwardly of the point of tangency of said underedge with a flat surface on which said toy is placed, the distance from the pivotal connection of said member to the back of the curved underedge being substantially greater than the corresponding distance to the forward portion of said underedge.

ROBERT SLEESMAN.
